UNITED STATES PATENT OFFICE.

FENTON WRIGHT, OF KANSAS CITY, MISSOURI.

COIN-ACTUATED CLOCK-BANK.

1,212,597.

Specification of Letters Patent. Patented Jan. 16, 1917.

Application filed November 27, 1915. Serial No. 63,777.

To all whom it may concern:

Be it known that I, FENTON WRIGHT, a citizen of the United States, residing at Kansas City, in the county of Jackson and State of Missouri, have invented certain new and useful Improvements in Coin-Actuated Clock-Banks, of which the following is a specification.

My invention relates to new and useful improvements in coin actuated clock banks, the primary object of my invention being the provision of a combined clock and coin bank so arranged that the clock or its alarm can be wound or set only after the proper coin has been inserted in the bank.

In this connection, a still further object of my invention consists in providing a novel casing adapted to surround the customary clock casing and so inclose the clock and also adapted to provide a coin receiving receptacle having a removable closure normally locked in place by a suitable form of key controlled lock.

A still further object of my invention is to slot the casing surrounding the clock and lock in such a manner that the levers of the clock, for regulating the clock and cutting off the alarm, may be accessible at all times, it being necessary to insert coins in the device only when the clock or alarm is to be wound or when the alarm is to be set, provision being made for setting the clock without reference to the coin actuated mechanism.

A still further object of my invention consists in providing the outer casing with key receiving openings in alinement with the squared terminals of the various winding and alarm setting arbors and in mounting within the casing a coin controlled stop plate which, in normal position, prevents movement of a key into engagement with such arbors, but which may, under certain conditions, be turned to bring openings in the plate into engagement with the openings in the casing to permit application of the key. In connection with the above stop plate, I provide a coin controlled mechanism which, when a proper coin is inserted through a slot in the casing, may be manually actuated to move the stop plate to bring its openings into registration with the openings in the casing, means being provided for automatically returning the stop plate to normal position when the manually actuatable means is released.

A still further object of my invention consists in the provision of a novel form of plug lock for securing the closure of the outer casing of the device in place and in the provision of a shield mechanism carried by the lock structure to protect the coin controlled mechanism from injury from accumulated coins in the bank chamber proper and also to prevent such coins interfering with access to the various arbors of the clock.

With these and other objects in view, my invention will be more fully described, illustrated in the accompanying drawings, and then specifically pointed out in the claims which are attached to and form a part of this application.

In the drawings: Figure 1 is a perspective view of my improved coin actuated clock bank; Fig. 2 is a central, vertical, longitudinal sectional view of the device; Fig. 3 is a transverse vertical sectional view taken on the line 3—3 of Fig. 2, looking in the direction of the arrows and showing the normal position of the coin controlled mechanism and the manner of inserting a coin therein; Fig. 4 is a view corresponding to Fig. 3, showing the coin controlled mechanism in an intermediate position; Fig. 5 is a fragmentary perspective view of the mechanism, shown in Figs. 3 and 4; Fig. 6 is a section on the line 6—6 of Fig. 2, looking in the direction of the arrows and illustrating the coin guard device; Fig. 7 is a similar view taken on the line 7—7 of Fig. 2, looking in the direction of the arrows and illustrating the method of securing the keeper member of the lock in the casing; Fig. 8 is a fragmentary longitudinal sectional view, showing the manner of applying a key to one of the arbors when the stop plate is in proper position; Fig. 9 is a plan view of the stop plate removed from the remainder of the device; Fig. 10 is a rear elevation of the removable closure of the device; Fig. 11 is a perspective view of the coin engaging and stop plate releasing lever removed from the stop plate; Fig. 12 is a perspective view of the coin guard; Fig. 13 is a fragmentary, central longitudinal section of the lock member proper of my improved plug lock; Fig. 14 is a transverse section on the line 14—14 of Fig. 13, showing the lock in normal position; Fig. 15 is a similar view, showing the lock in released position; Fig. 16 is a fragmentary longitudinal sectional view through the lock proper, showing the lock in

position in full lines and in released position in dotted lines.

Corresponding and like parts are referred to in the following description and indicated 5 in all the views of the drawings by the same reference characters.

For a general understanding of the construction and arrangement of parts, attention is first directed to Figs. 1 and 2 of the drawings. In these figures, 10 indicates a 10 clock of any suitable type, the one in the present case being of the alarm type having an alarm gong 11 supported in spaced relation to the back of the clock by a suitable bracket 12, the gong being formed with 15 openings 13 for the passage of the various winding and alarm setting arbors 14. Surrounding this clock is the casing proper of my device, indicated as a whole by the numeral 15 and including a cylindrical body member closely encircling the same and open at its ends, the clock, as clearly shown in the drawings, being located in one end of the casing in such a manner that its face 20 forms a closure for such end of the casing. This casing is provided with suitable slots 16 to receive the regulating lever 17 by means of which the clock may be regulated and the alarm mechanism cut into and out 25 of operation. To insure the gong being clearly heard, the casing is provided intermediate its length with a series of circumferentially spaced openings 18. A partition wall 19 divides the casing into forward and 30 rearward chambers, the clock being located in the former and the latter constituting the coin receiving chamber, as will be later explained. This partition fits snugly within the casing 15, is secured in place by brackets 35 35 or other suitable means and is formed with openings 21 in alignment with the arbors 14 of the clock. In order that the clock may be set, the arbor 22, which is the one which must be turned to set it, is provided 40 with a beveled gear 23 which meshes with a beveled gear 24 carried upon a shaft 25 journaled in a vertically disposed bearing 26 with its free end terminating in proximity to and in alignment with one of the openings 18. This free end of the shaft or arbor 25 is provided with a transverse pin 27 in order that it may be operatively engaged and the shaft turned by a key 28. This key, 50 which is shown in Fig. 8 of the drawings, has its stem portion formed with a cylindrical socket 29 to receive an arbor and with a diametric slot 30 to straddle the pin 27 of such arbor.

The various clock and alarm winding and 60 alarm setting arbors 14, instead of being provided with the usual fixed keys, whereby they may be turned, are formed with extensions 31 which may be integral parts of the arbors if the clock is purposely made for my device or which may be separably formed,

as shown in the present case and threaded upon the arbors. In any event, the extensions 31 of the arbors project to the rear of the casing 15 and are, at their free ends, provided with cross pins 32 in order that they 70 may be rotated by the key 28, previously described, this key, therefore, serving not only for setting the clock, but also for winding the clock and alarm and for setting the alarm.

The rear end of the casing 15 is closed by a removable cap or closure 33, the peripheral flange of which is reduced in thickness at its free edge to seat within the rear end of the casing 15 and to provide a stop shoulder to limit its inward movement when applied. The inner face of the casing 15, at one point, is provided with a longitudinal groove 34 to receive a key or feather 35 formed upon the reduced portion of the cap 80 flange in order to insure the application of the cap in identically the same manner under all circumstances in order that key receiving openings 36, formed in the body of the cap, may be in alignment with the clock 90 arbors 31. This cap is secured in place by a plug lock mechanism 37 carried by the cap and co-acting with a keeper 38 carried by or formed upon the partition wall 19 of the casing.

The body portion of the cap 33 is provided centrally with an opening 39 to receive the escutcheon 40 of the lock and this escutcheon is formed upon the outer end of a cylindrical lock housing 41 which projects 100 at its other end in spaced relation to the partition wall 19 when the cap is in place, as best shown in Fig. 2. The escutcheon 40 is formed centrally with a circular opening 41 to permit the rotation of the shank 42 of a 105 key 43 and with diametrically disposed radial slots 44 extending into the opening 41 to receive the laterally extending lock wards 45 which are preferably of unequal length, as shown in Fig. 13. Referring 110 more particularly to Figs. 13 to 16 inclusive for the lock structure, it will be clear that the housing or casing 41 incloses the rotatable plug 46 having openings 47 in its outer end to receive the free ends of the wards 45 115 of the key and a central opening or socket 48 to receive the intermediate ward or centering ward 49 of the key. The openings 47 of the rotatable plug 46, at their ends opposite the escutcheon, open into cylindrical sockets 50 in which are slidably mounted cylindrical pins 51 which are so proportioned that when the key is properly forced into the lock, their ends remote from the key will lie flush with that end of the rotatable plug 46 opposite the escutcheon. Mounted within the lock casing 41 is a second but fixed plug 52 provided in one end with cylindrical sockets 53 in the inner ends of which are seated light helical springs 54 120 125 130

which engage against drivers 55 in such a manner that in normal position of the lock the opposite ends of the drivers seat in the adjacent aligned ends of the sockets 50 of the 5 rotatable plug. By forcing the key against the pins 51, the latter may be moved to force the drivers against the action of their springs until they lie wholly within the fixed plug 52 when the rotatable plug may be turned by turning the key. The fixed 10 plug 52 is secured in the casing by any suitable means, such as the set screw 56 in such a manner that it can neither turn nor move longitudinally. This fixed plug is provided 15 throughout its length with a longitudinal channel 57 and a locking lever 58 is pivoted intermediate its length in this channel, as shown at 59. This locking lever is provided with a reduced cylindrical extension 60 at 20 one end to receive a roller 61 which seats in a cam slot 62 formed in the adjacent end of the rotatable plug 46, one end of the cam slot being at the center of the plug and the opposite end opening through the peripheral 25 face thereof. It will, therefore, be clear that turning of the rotatable plug in the proper direction will move that end of the lever received by it from a central to a peripheral position and will, consequently, 30 move the opposite end of the lever in an opposite direction. The opposite or outer end of the locking lever 58 terminates in an outwardly directed hook 63 which projects beyond the casing 41 and within an annular 35 locking collar 64 carried by or formed integrally with the partition wall 19 and centrally thereof. This locking collar 64 is formed with an inwardly directed peripheral locking shoulder 65 to be engaged by the 40 hook 63 and the outer face of this shoulder is beveled, as shown at 66 to facilitate application of the lock.

As will be clearly seen by reference to Fig. 2 of the drawings, the winding and setting arbors of the clock, at their free ends, terminate somewhat short of the body portion of the cap 33 and one of the features of my present invention consists in the provision of a stop plate or equivalent mechanism between such ends of the arbors and the cap which will normally prevent access to the arbors through the openings 36 of the cap, but which, when released by application of a proper coin may be moved to permit such access. For an understanding of this coin controlled stop mechanism, attention is more particularly directed to Figs. 3 to 5 inclusive of the drawings. As will be seen by reference to these figures, I provide 50 a stop plate, indicated as a whole by the numeral 67 which is rotatably mounted about the lock housing 41 and which bears against the inner face of the body portion of the cap. This plate is circular in shape 55 and of less diameter than the casing 15 and

at diametrically opposite points is formed with wings 68 and 69, the arcuate edges of which are spaced a slight distance from the inner face of the flange of the cap 33. This plate is formed with openings 70 which may be brought into alignment with the openings 36 of the cap by means of a handle 71 secured to the wing 68 and movable in an arcuate slot 72 formed in the cap, whereby the plate may be partially rotated. A spring 73 is connected at one end to the inner end of the handle 71, which handle preferably projects through the plate, and at its other end to a pin or screw 74 carried by the cap or by a fixed member secured to the cap, 80 this spring tending to hold the stop plate at one extreme limit of its movement with its openings out of alignment with the openings of the cap. The plate is held against inward movement partially by the engagement of the enlarged outer end of the handle against the outer face of the cap and at its other side by an arcuate locking plate 75 secured by upturned ears 76 to the inner face of the cap flange in such a manner that the locking plate is spaced from the inner face of the cap body a distance slightly greater than the thickness of the stop plate 67 in order that the wing 69 of such plate may move between it and the cap. 90

A locking lever of the bell crank type, indicated as a whole by the numeral 77, is pivotally mounted intermediate its length upon the inner face of the stop plate 67, as shown at 78, the inner edge of one arm 79 being curved to engage against the inner edge of the locking plate 75 and the opposite arm 80 being laterally offset to extend over the upper face of the locking plate 75. The arm 79 of the lever, adjacent its free end, is formed with an upturned stop lug 81 and a spring 82 fixed at one end to the plate 67 engages this lug to normally hold the arm 79 in engagement with the locking plate 75 in which position the arm 80 extends radially to a position just short of the cap flange. 100 The locking plate, adjacent its outer peripheral edge, is provided with an upstanding locking lug 83 which projects in the path of movement of the lever arm 80 when the plate 67 is being rotated in such a manner that after a partial rotation, but before it has been turned sufficiently to bring its openings into alignment with the openings of the cap, the lug will engage the locking lever to normally prevent further turning of the plate 67. 110 The locking lever 77 has its arm 79 also formed with an oppositely directed coin engaging lug 84 which seats against the inner face of the body of the cap 33, the stop plate 67 being cut-away at this point to form a coin receiving pocket or seat 85. The flange portion of the cap 33 is formed with a coin slot 86 at such a point that in normal position of the stop plate 67, that is 120

125 130

the position in which it is held by the spring 73, a coin of suitable size passed through the slot will enter the pocket 85 of the stop plate and engage one corner of such pocket 5 and the lug 84 of the locking lever before the coin has fully passed within the cap. Under these conditions, upon the initial turning movement of the locking plate by means of the handle 71, the coin will be forced 10 farther into the pocket, as will be appreciated by examining Figs. 3 and 4 and during such movement, will, because of its engagement with the coin lug 84 of the locking lever, swing the locking lever in such a 15 manner as to swing its arm 80 inwardly and permit the locking lever to pass the locking lug 83 of the locking plate 75. The stop plate 67 being thus released, it is possible to turn it to its full extent to bring its openings 20 in alinement with the openings of the cap and thereby permit application of the key 28 to any of the winding arbors or alarm setting arbors desired. To facilitate the discharge of the coin from the pocket 85 into 25 the chamber between the cap and partition 19, the locking plate, at its upper end, has its under face beveled, as shown at 87 in order that the coin may be tilted inwardly toward the receptacle as it passes out from 30 beneath the locking plate 75 and to cause such tilting I provide a cam 88 which I secure to the inner face of the cap in alinement with the locking plate and with its wedge end disposed in slightly overlapped spaced 35 relation with respect to the adjacent end of the locking plate. The coin engaging the edge end of this cam member 88 is deflected in such a manner as to pass between the locking plate and cam and be discharged into the 40 casing.

In order to avoid any possibility of injury to or disarrangement of the coin controlled mechanism above described by loose coins contained in the bank and further to prevent such coins interfering with the application of the key 28 to the various arbors of the clock, I provide a coin guard, best shown in Figs. 6 and 12 of the drawings. This coin guard includes a tubular portion or housing 45 89 adapted to surround and be secured to the lock housing 41 and carrying smaller tubular housings 90 adapted to surround the arbors 31 of the clock, but of sufficient size to permit the insertion of the stem of the key 28 and its application to the arbors. A guard plate 91 is secured to that end of the housing 89 adjacent the cap 33, being formed with openings alining with the tubular housings 90 and being further formed with a 50 radial slit defining edge portions which are reversely bent, as shown at 92 to provide a coin passage or slot 93. This plate is so disposed that this slot 93 is in position for the receipt and transference of a coin passing

from beneath the locking plate 75 and coins 65 discharged from such plate pass through the slot 93 and into the space between the guard plate 91 and partition wall 19.

The foregoing description, taken in connection with the drawings, will afford such an understanding of the operation of my device as will render any detailed description thereof unnecessary. Assuming that the cap is locked in position, whenever it becomes necessary to wind the clock or the alarm 70 or to set the alarm, access may be had to any desired arbor or to all of the arbors by inserting a coin of the proper size in the slot 86 until it seats in the pocket 85 of the stop plate and engage the lug 84 of the locking 75 lever 77. The stop plate is then turned by means of the handle 71 against the tension of the spring 73 until its openings are in alinement with the openings of the cap, the coin swinging the locking lever in such a 80 manner that it does not engage the locking lug 83 to prevent its turning and subsequently being discharged through the slot 85 of the guard plate 91. The person operating the device may then, while still holding the plate against counterturning under the action of the spring 73, apply the key 90 to any or all of the arbors to perform the operations desired, after which the key is withdrawn and the handle of the stop plate 95 released when the plate will return to normal position. At any time, the accumulated coins may be removed from its chamber by applying the key 43 to the plug lock in the manner previously described to release such lock and permit removal of the cap 33 which also carries the lock and coin 100 controlled mechanism.

Obviously, many changes in the details of construction may be made without affecting 105 the primary principles of operation of my device and I therefore retain the right to make any changes within the scope of the appended claims without in the slightest degree departing from the spirit of my invention.

Having thus described the invention, what is claimed as new is:

1. A coin controlled mechanism including a casing having an opening, a stop plate rotatably mounted in the casing and having an opening adapted to register with that of the casing, means for normally holding the stop plate with its opening out of registration with that of the casing, the casing being formed with a coin admitting slot, a locking plate mounted in the casing and coacting with one wall thereof to form a passage for a coin admitted through the slot, a locking lug carried by the locking plate, and a spring pressed lever normally engageable with the locking lug upon turning of the stop plate, said lever being engageable by a 110
2. A coin controlled mechanism including a casing having an opening, a stop plate rotatably mounted in the casing and having an opening adapted to register with that of the casing, means for normally holding the stop plate with its opening out of registration with that of the casing, the casing being formed with a coin admitting slot, a locking plate mounted in the casing and coacting with one wall thereof to form a passage for a coin admitted through the slot, a locking lug carried by the locking plate, and a spring pressed lever normally engageable with the locking lug upon turning of the stop plate, said lever being engageable by a 115
3. A coin controlled mechanism including a casing having an opening, a stop plate rotatably mounted in the casing and having an opening adapted to register with that of the casing, means for normally holding the stop plate with its opening out of registration with that of the casing, the casing being formed with a coin admitting slot, a locking plate mounted in the casing and coacting with one wall thereof to form a passage for a coin admitted through the slot, a locking lug carried by the locking plate, and a spring pressed lever normally engageable with the locking lug upon turning of the stop plate, said lever being engageable by a 120
4. A coin controlled mechanism including a casing having an opening, a stop plate rotatably mounted in the casing and having an opening adapted to register with that of the casing, means for normally holding the stop plate with its opening out of registration with that of the casing, the casing being formed with a coin admitting slot, a locking plate mounted in the casing and coacting with one wall thereof to form a passage for a coin admitted through the slot, a locking lug carried by the locking plate, and a spring pressed lever normally engageable with the locking lug upon turning of the stop plate, said lever being engageable by a 125

coin admitted through the slot to be moved to a position where it will not engage the lug.

2. A coin controlled mechanism including a casing having an opening, a stop plate rotatably mounted in the casing and having an opening adapted to register with that of the casing, means for normally holding the stop plate with its opening out of registration with that of the casing, the casing being formed with a coin admitting slot, a locking plate mounted in the casing and co-acting with one wall thereof to form a passage for a coin admitted through the slot, a locking lug carried by the locking plate, and a spring pressed lever normally engageable with the locking lug upon turning of the stop plate, said lever being engageable by a coin admitted through the slot to be moved to a position where it will not engage the lug, and a guard wall located adjacent one wall of the casing and provided with a slot through which the coin admitted is discharged into the body of the casing.

3. A coin controlled mechanism including a casing having an opening, a stop plate ro-

tatably mounted in the casing and having an opening adapted to register with that of the casing, the casing being formed with a coin admitting slot and passage, and a locking lever normally holding the stop plate against turning and engageable by a coin moving through the passage to release the stop plate.

4. A coin controlled mechanism including a casing having an opening, a stop plate rotatably mounted in the casing and having an opening adapted to register with that of the casing, means for normally holding the stop plate with its opening out of registration with that of the casing, the casing being formed with a coin admitting slot and passage, a lug projecting within the casing, a locking lever pivoted upon the stop plate and normally engaging the lug to prevent rotation of the stop plate, the lever being engageable by a coin forced into the passage and by such engagement to be moved out of engagement with the lug and free the stop plate, and means for turning the stop plate when freed.

In testimony whereof, I affix my signature.
FENTON WRIGHT. [L.S.]
